UNITED STATES PATENT OFFICE.

HARRY E. SPENCER, OF NEW YORK, N. Y., ASSIGNOR TO ERNEST M. CULP, OF PATERSON, NEW JERSEY.

SHEET-METAL PUMP-BASE.

1,290,796.

Specification of Letters Patent.

Patented Jan. 7, 1919.

Application filed February 24, 1917. Serial No. 150,701.

To all whom it may concern:

Be it known that I, HARRY E. SPENCER, a citizen of the United States, and a resident of the borough of Manhattan, city, county, 5 and State of New York, have invented certain new and useful Improvements in Sheet-Metal Pump-Bases, of which the following is a full, clear, and exact description.

This invention relates to improvements in 10 air pumps, and more particularly to hand-operated pumps for use in inflating pneumatic tires.

The object of this invention is to provide a 15 simple and rigid sheet metal pump base constructed so as to permit the permanent mounting thereon of the pump barrel and a discharge nozzle adapted for connection with the usual air hose, and having a by-pass or exhaust passage connecting the lower 20 end of the pump barrel with the discharge nozzle.

A further object of the invention is to provide a pump base of the character set forth comprising simple and easily constructed 25 parts adapted to be stamped or pressed from sheet metal blanks and permanently connected together by welding or brazing.

In the drawings, Figure 1 is a top plan view of the pump base, showing the pump 30 barrel and discharge nozzle mounted thereon;

Fig. 2 a vertical sectional view on the line II—II of Fig. 1;

Fig. 3 a similar view on the line III—III of Fig. 1;

Fig. 4 a detail plan view of the plate 35 forming the by-pass or exhaust passage between the cylinder and nozzle; and

Fig. 5 is a side elevation of the pump.

The pump base comprises a body part 1 40 of sheet metal having a depending flange or rim 2 extending around the outer edges thereof. The base 1 is substantially oblong and adjacent each end thereof a portion of the body part of the base is stamped or otherwise shaped to form apertures 3, bounded by depending flanges 4. The flanges 2 and 4 support the body part 1 above the floor or ground and also serve to brace and strengthen the sheet metal base.

50 The central portion of the body part 1 of the pump base is stamped out to form a circular aperture 5 and an upwardly extending annular flange 6. The lower open end of the pump barrel or cylinder 7 fits within 55 the annular flange 6 and is preferably per-

manently connected therewith by welding or brazing.

The base 1 is cut away to form a circular aperture 8 adjacent the aperture 5 adapted to receive the lower end of a suitable discharge nozzle or nipple 9. The nipple 9 is preferably formed with an annular flange 10 adjacent its lower end adapted to rest upon the upper surface of the base 1 and to be welded or brazed to the base to permanently secure the nipple to the base. The upper end of the nipple 9 is threaded or otherwise adapted for connection with the usual air hose employed with pumps of this type and a suitable outwardly opening check 60 valve may be mounted in the nipple, or in the end of the air hose, as preferred.

A plate 10 of sheet metal is welded or brazed to the under side of the base 1 so as to cover the apertures 5 and 8. The plate 10 65 is pressed or stamped to form a depression 11 therein extending from a point below the aperture 5 to a point below the aperture 8 to form a by-pass or discharge passage 12 connecting the lower open end of the pump 70 cylinder 7 with the lower end of the nipple 9. The plate 10 is secured to the base 1 by welding or 75 brazing.

Any suitable means may be provided for admitting air beneath the pump piston on the upward movement thereof, such, for example, as an apertured cap at the upper end of the cylinder and a loosely fitting piston carrying a flexible inverted cup-shaped washer, such as is commonly employed in 80 pumps of this type.

From the foregoing it will be observed that an exceedingly light and strong pump base is provided, comprising a few readily assembled parts adapted to be readily stamped, pressed, or otherwise formed from 85 sheet metal.

An important feature of the invention is the construction and arrangement of parts whereby the discharge nozzle may be mounted on the base and connected with the lower end of the pump barrel, thus permitting the use of a sheet metal base on a pump in which air is discharged from the lower end of the pump barrel on the down stroke of the piston, without the necessity of employing 100 two telescoping pump cylinders, or other comparatively complicated mechanism, such as heretofore used.

It will also be observed that the depending marginal flanges 2, and the depending 110

flanges 4 at each side of the pump barrel socket serve to support the base plate 1 in an elevated position to enable the plate 10, having the depressed portion 11 forming 5 the exhaust passage, to be secured to the under side of the base plate. The flanges 2 and 4 also serve to stiffen the base plate. It will be further observed that the flanges 4 support the plate 1 at each side of the 10 pump cylinder and thus prevent bending or buckling of the plate under pressure of the foot of the operator.

Having thus described my invention, I claim as new and desire to secure by Letters 15 Patent:—

1. A base for pumps comprising a sheet metal body member having a depending marginal flange and also having apertures adapted to communicate with the pump cylinder and discharge nozzle, and a metal plate member secured to the under side of the body member and extending across both of said apertures, one of said members having a pressed-up portion forming with the 25 other member a passage connecting said apertures with each other.

2. A base for pumps comprising a sheet metal body member having a depending marginal flange and also having apertures 30 adapted to communicate with the pump cylinder and discharge nozzle, and a metal plate member secured to the under side of the body member and extending across both said apertures, said plate member having a

pressed-up portion extending from one to 35 the other of said apertures and forming with the body member a passage connecting said apertures with each other.

3. A base for pumps comprising a sheet metal body member having a depending 40 marginal flange and also having apertures adapted to communicate with the pump cylinder and discharge nozzle, said member also having openings between which said apertures are located and a depending supporting flange around the margin of each such opening, and a metal plate member secured to the under side of the body member and extending across both said apertures, said members having between them 45 a by-pass connecting said apertures with each other.

4. A sheet metal base for pumps comprising a body part having a depending marginal flange and a centrally arranged 55 aperture, an integral upwardly extending annular flange surrounding said aperture adapted to receive the lower open end of the pump cylinder, a nipple secured to said body part and having its lower end seated in a second aperture in the body part, and a metal plate secured to the under side of the body part and extending across both of said apertures, said plate having a channel therein 60 communicating with both of said apertures. 65

In testimony whereof I hereunto affix my signature.

HARRY E. SPENCER.
